PATENTED MAY 7, 1907.

E. E. & H. L. STROTHMAN.
SHAKING AND DUMPING GRATE.
APPLICATION FILED OCT. 10, 1905.

UNITED STATES PATENT OFFICE.

EDWARD E. STROTHMAN AND HERBERT L. STROTHMAN, OF SUPERIOR,
WISCONSIN.

SHAKING AND DUMPING GRATE.

No. 852,467.

Specification of Letters Patent.

Patented May 7, 1907.

Application filed October 10, 1905. Serial No. 282,138.

To all whom it may concern:

Be it known that we, EDWARD E. STROTHMAN and HERBERT L. STROTHMAN, citizens of the United States, residing at Superior, in the county of Douglas and State of Wisconsin, have invented certain new and useful Improvements in Shaking and Dumping Grates; and we do hereby declare the following to be a full, clear, and exact description of the invention, such as will enable others skilled in the art to which it appertains to make and use the same.

Our invention relates to shaking and dumping grates for furnaces and has for its object the provision of a grate-bar provided with an adjustable trunnion.

It has for a further object the provision of a rocking shield mounted on the side bar of a shaking or dumping grate and adapted to be engaged and operated by the grate bar.

It has for a further object the provision of a shield adapted to overlie the trunnion bearing on said side bar and to protect the same from excessive heat and to form a fire bearing surface and containing draft passages.

With these and other objects in view, it consists of the constructions, combinations, and arrangements of parts hereinafter described and claimed.

In the accompanying drawings, Figure 1 is a perspective view, partly broken away, of our improved grate bar. Fig. 2, is a central longitudinal vertical section through the adjoining ends of the grate bars of a double grate, showing the central or common supporting bar in cross section. Fig. 3, is a side elevation of a portion of the side bar of said grate, showing one form of our improved rocking shield in normal position and also in rocking or dumping position. Fig. 4, is a detail perspective view of said shield. Fig. 5, is a side elevation of a portion of a modified form of said side bar, and of a modified form of my improved shield in normal position and also in rocking or dumping position. Fig. 6 is an enlarged detail perspective view of said modified form of shield, and Fig. 7, is an enlarged detail opposite perspective view of said modified form of shield.

In said drawings, 1, represents a side supporting frame or bar, which may be exactly similar to the central supporting bar 1^a of a double grate, or may, if desired, have a flush outer face. It is obvious that a bar similar

to the central bar may, if desired, be used as 55 a side bar, but if the side bar have one flush side face it would not be as desirable for use as the central bar of a double grate. Said side and central supporting bars are transversely apertured or recessed at intervals, as 60 at 1^b for the reception of the trunnions of the adjoining grate bars, and said apertures, instead of being slots open at the upper edge of the bar, are preferably circular, in which case the supporting bars will hold the grate bars 65 down and prevent them from jumping out of engagement with the supporting bars. Concentric bosses 1^c are preferably formed around said recesses or apertures in the supporting bars to afford broader bearings for the trunnions of the grate bars, and in the form of 70 said invention shown in Fig. 3, said bosses form fulcrums for corresponding shields 5. In the modified form of said invention shown in Fig. 5, lugs are preferably formed on one 75 face or the other of the supporting bar at the position 1^d to operate as pivots for the corresponding modified shields; but it is obvious that said modified supporting bars may be apertured at 1^d instead of being provided 80 with such lugs, and that equivalent lugs may be formed on the shields to engage such apertures; or separate pivots may be projected through the modified shields and through 85 said modified bars at the points 1^d to form supports for the fulcrums of such shields, these various forms of attaching said modified shields to the modified supporting bars being regarded as equivalents within the 90 spirit and scope of my invention.

The grate bars 2 are longitudinally apertured at one end as at 2^a to receive a sliding trunnion 3, which in operation is adapted to be partly projected into corresponding recesses or apertures 1^b in the side or central 95 supporting bars 1 or 1^a. Said trunnion may be secured in operative position by any suitable means, as by a push spring 4, or by a locking pin 3^a extending from said trunnion through a downwardly opening transversely 100 directed slot 2^b formed in said grate bar at an angle to, and communicating with the trunnion passage 2^a. Said slot 2^b communicates with an outwardly opening longitudinally directed slot 2^c formed in the side of said 105 bar and extending parallel to, and communicating with said passage 2^a. It will be obvious that when the trunnion is projected and

the pin 3^a is in the slot 2^b said trunnion will be held in its projected position, but that when said pin is manually swung upwardly in said slot 2^b and backwardly along the slot 5 2^c it will recede said trunnion and disengage it from the side or central supporting bar. Said sliding trunnion may be provided at each end of the grate bars, or, if desired one, end of each bar may be provided with a fixed 10 trunnion as 3^c.

Mounted on the side or central supporting bars, or both, are rocking or dumping fire-bearing shields 5, or 6. Said shields comprise the body portion 5, preferably grated or 15 provided with draft passages as at 5^a, and recessed or notched at each end as at 5^b, which notches are adapted to engage operating lugs 2^d and 2^e formed upon the ends of the adjoining grate bars. Said shields 5 are 20 also provided on one or both sides with a lug or lugs 5^c partly concentric with and adapted in operation to engage the boss or bosses 1^c on one or both sides of the side or central supporting bar, said boss or bosses forming 25 the point of resistance upon which said shield is fulcrumed. Thus, where the grate bar is rocked in the proper direction, one of the lugs, as 2^d, raises one end of the shield 5, which pivots upon the boss 1^c and is held 30 thereby in proper position. When the grate bar is rocked back to normal position, the opposite lug 2^e tips the shield 5 back to normal position. If desired either the lug 2^d or 2^e may be omitted when using the shield 5, de- 35 pending upon relative setting of the shield 5 to the grate 2, and the shield returned to normal position by gravity.

The shield shown in Figs. 5, 6, and 7 is of somewhat different construction from that 40 just described. It consists of the body portion 6, having legs 6^a formed thereon at one end adapted to straddle the side or central supporting bar. A lip 6^b is provided upon one side of said body portion near the opposite end thereof and a lug 6^c is formed upon the opposite side of said body portion at said opposite end by which it is adapted to be pivoted to the side or central supporting bar, as by engagement with one of the lugs at 1^d. 45 Said shield 6 is preferably grated, as at 6^d, to form draft passages, and bars 6^e are preferably formed across the front of said legs to prevent the entry of clinkers between them. One of the lugs, as 2^e, formed on the end of 50 the adjoining grate bar is adapted to engage the free end of said shield 6 and, when said grate is rocked in the proper direction, to tilt said free end of the shield 6 upward. The shield 6 will usually fall to normal position 55 by gravity when the grate bar is rocked back to normal position, but we prefer to form feet 6^f upon said legs 6^a, which feet, or one of them may be engaged when necessary by the descending lug 2^e, to start or force the lifted 60 end of the shield downward. The position 65

of the lugs 1^d and 2^e may be varied, as may be suitable and desired, with regard to radial distance and direction from the longitudinal axis of the respective said grate bars, and the dimensions and proportions of all or 70 any of the parts of our said invention may be varied, as may be suitable and desired, without departing from the spirit and scope of our said invention. As will be observed the shields preferably do not contact at all points 75 along their under faces with the upper edge of the side or central bars, but space is left between the greater part of said under faces and said upper edge of the supporting bar, either by arching the shields as at X or by 80 cutting away the edge of the supporting bar, as at Y, or both. Such spaces form air passages, and, to a degree, a means of escape for fine ash, as well as serve to lighten the weight of the parts. If said grate bars are provided 85 with slidable trunnions only at one end, such bars may, after the withdrawal of the slideable trunnions, be drawn endwise sufficiently to disengage the fixed trunnion from the opposite supporting bar. Said grate 90 bars may be rocked or dumped by any suitable means, as but a connecting bar 7, engaging hooks 8 formed on said grate bars, and operated by a draw or push rod 9.

The operation of said invention will be 95 clear from the foregoing description.

Having now described our invention, what we claim and desire to secure by Letters Patent is,

1. In a dumping grate, the combination of 100 a grate bar having a recess formed in one of its ends, a slot extending upwardly through the lower edge of said bar and partly through said bar in a transverse direction, said bar having a slot formed through one of its sides 105 communicating with said recess and with the first said slot, a sliding trunnion in said recess, and a pin engaging said trunnion and adapted to be operated to project or retract said trunnion and to extend through one or 110 the other of said slots according to the position of said trunnion, and a push spring in said recess adapted to normally hold said trunnion in a projected position.

2. In a dumping grate, the combination of 115 a grate bar having a recess formed in one of its ends, a slot communicating upwardly with said recess and opening downwardly through the lower edge of said bar and extending partly through said bar in a trans- 120 verse direction, said bar having a slot formed through one of its sides communicating with said recess and with the first said slot, a sliding trunnion in said recess, and a pin engaging said trunnion and adapted to be operated 125 to project or retract said trunnion and to extend through one or the other of said slots according to the position of said trunnion.

3. In a dumping grate, the combination of 130 a relatively stationary support, rocking

- shields mounted on said support, rocking
grate bars mounted on said support inde-
pendently of said shields and provided with
means adapted to engage said shields to rock
5 the same.
4. In a dumping grate, the combination of
a relatively stationary support, rocking
shields mounted on said support and adapted
to fulcrum thereon, rocking grate bars
10 mounted on said support independently of
said shields and having lugs formed on their
ends adapted to engage said shields and rock
the same.
5. In a dumping grate, the combination of
15 a relatively fixed support having a boss
formed thereon, a shield mounted on said
support and provided with a lug adapted to
engage on said boss, and means for rocking
said shield on its support.
- 20 6. In a shaking and dumping grate, the
combination with a grate support, a grate
bar having a trunnion engaging said support,
a trunnion shield comprising a body portion
25 provided on one side intermediate of its ends
with a depending lug.
7. In a dumping grate, the combination
with a suitable grate support of a rocking
shield pivotally mounted thereon and com-
30 prising a body portion, legs depending from
one end, a lug on one side at the opposite end,
and a lug or lip upon the opposite side inter-
mediate of the ends.
8. In a dumping grate, the combination
35 with a suitable relatively stationary support,
of a rocking shield pivotally mounted there-
on and provided with depending legs at one
end adapted to engage said support, a grate
- bar journaled on said support independently
of said shield and adapted to engage said 40
shield to rock the same on its pivot.
9. In a shaking or dumping grate, the
combination of supporting bars; grate bars
provided with trunnions journaled in said
supporting bars; trunnion covers for each of 45
said trunnions, each of said covers comprising
a grated trunnion - covering portion,
legs adapted to straddle one of the said sup-
porting bars and adapted at their free ends or
feet to extend beneath the trunnion over 50
which said cover extends, and to there en-
gage a projecting portion formed on said sup-
porting bar; means for coupling a number of
said grate bars together and adapted to rock
the same on their bearings, and means for op- 55
erating said rocking means.
10. In a shaking and dumping grate, the
combination of supporting bars; grate bars
having trunnions journaled in said support-
ing bars, said supporting bars each having 60
lugs formed upon one of their side faces;
trunnion covers for said trunnions, each com-
prising a grated trunnion covering portion,
and depending portions adapted to straddle
one of said supporting bars, the free end of 65
one of said depending portions being adapted
to extend under one of said lugs; and means
for rocking said grate bars.

In testimony whereof we hereunto affix
our signatures, in presence of two witnesses. 70
